DESIGN FOR A TOY MACHINE GUN

Merrill R. Pattison, Seattle, Wash.

Application October 12, 1944, Serial No. 115,744

Term of patent 14 years

(Cl. D34—15)

To all whom it may concern:

Be it known that I, Merrill R. Pattison, a citizen of the United States of America, residing at Seattle, in the county of King and State of Washington, have invented a new, original, and ornamental Design for Toy Machine Guns, of which the following is a specification, reference being had to the accompanying drawing, forming part thereof.

Figure 1 is a perspective view of a toy machine gun, showing my new design with the two magazines in intermediate position.

Figure 2 is a plan view thereof showing both magazines in their lower positions.

Figure 3 is a front elevational view thereof showing one magazine in its upper position and the other magazine in its lower position.

I claim:

The ornamental design for a toy machine gun, as shown.

MERRILL R. PATTISON.
